UNITED STATES PATENT OFFICE.

JOHN J. DE LANCEY, OF BINGHAMTON, NEW YORK.

EXHAUST-NOZZLE FOR LOCOMOTIVES.

SPECIFICATION forming part of Letters Patent No. 442,767, dated December 16, 1890.

Application filed March 15, 1890. Serial No. 344,011. (No model.)

To all whom it may concern:

Be it known that I, JOHN J. DE LANCEY, of Binghamton, in the county of Broome and State of New York, have invented a new and 5 Improved Exhaust-Nozzle for Locomotives, of which the following is a full, clear, and exact description.

The object of the invention is to provide a new and improved exhaust-nozzle for locomotives, serving to regulate the exhaust of the engines, and thereby regulating the draft in the boiler.

The invention consists of certain parts and details and combinations of the same, as will 15 be hereinafter fully described, and pointed out in the claims.

Reference is to be had to the accompanying drawings, forming a part of this specification, in which similar letters of reference indicate 20 corresponding parts in all the figures.

Figure 1 is a side elevation of the improvement as applied to a locomotive, parts being broken out. Fig. 2 is an enlarged plan view of the improvement. Fig. 3 is a transverse 25 vertical section of the same. Fig. 4 is a sectional side elevation of the same on the line $x x$ of Fig. 2, and Fig. 5 is a plan view of a modified form of the plate.

The improved exhaust-nozzle A is provided 30 with a plate B, fitted onto the upper end of the exhaust-pipe C, which may be double, as is illustrated in Fig. 3, or single—that is, the two exhausts of the engines of the locomotive running into a single exhaust-pipe.

The plate B is provided with apertures D 35 of the same size as the apertures at the upper ends of the exhaust-pipe C, so that when the plate B is in a central or normal position the apertures D of the plate B fully register with 40 the openings in the end of the exhaust-nozzle. The plate B is fulcrumed in its middle on a pin E, projecting from a bar F, supported on brackets G, secured to the sides of the exhaust-pipe C, the said plate being held in 45 place on the brackets by nuts H, screwing on the threaded ends of the said brackets G, as is plainly illustrated in Fig. 4. The pin E, after passing through the plate B, also passes a short distance into the top of the exhaust- 50 pipe C, so as to form a secure bearing for the plate B. On the top of the latter, at its sides in the middle, are arranged offsets I, onto

which fits the under side of part of the bar F in such a manner that the plate B is free to turn on its pivot E, and at the same time is 55 held securely against the upper end of the exhaust-pipe C to prevent the plate from being lifted upward by the force of the exhaust steam.

From the plate B projects to one side an 60 arm J, pivotally connected by a link K with a lever L, fulcrumed on the outside at the front end of the locomotive-boiler, the link K passing through the said front end. The lever L is also pivotally connected by a link N, 65 extending along the outside of the locomotive, with a lever O, pivoted on the cab of the locomotive and extending into the same so as to be within convenient reach of the engineer in charge of the locomotive. The lever O is 70 adapted to be locked in place in any desired position by the usual arrangement connected with a notched segment P, as shown in Fig. 1.

When the lever O stands in a vertical position, as illustrated in the said figure, the 75 openings D in the plate B fully register with the openings in the exhaust-pipe C. In this position the exhaust-steam can pass freely out of the exhaust-pipe C through the smoke-box and smoke-stack of the locomotive, so as 80 to cause considerable draft in the fire-box of the boiler. When it is desirable to increase the amount of draft in the fire-box of the locomotive, the engineer in charge of the locomotive operates the lever O either forward or 85 backward, so that the lever L swings and imparts a swinging motion by the link K and the arm J to the plate B, which latter moves across the top of the exhaust-pipe C, and part 90 of the openings of the latter are cut off or diminished in size, so that the exhaust of the engine is retarded, and consequently the draft in the smoke-box and smoke-stack is increased, so that a consequent increase of the draft takes place in the fire-box of the locomotive. 95

It will be seen that the two openings in the exhaust-pipe are diminished in size alike by moving the plate B, and it is immaterial in which direction the engineer moves the lever 100 O, as the cut-off takes place either way. When the exhaust-pipe C is single, the plate B is preferably arranged as shown in Fig. 5, having but one single opening D, and pivoted at

- one end to the pin E and provided at the opposite end with the arm J. A segmental slot Q is also formed on the plate B, and into it extends a pin R, held on the exhaust-pipe 5 and serving to limit the swinging motion of the plate B, which is operated from the cab of the locomotive by the engineer in the same manner as the double plate previously described.
- 10 Having thus fully described my invention, I claim as new and desire to secure by Letters Patent—
- 15 1. The combination, with an exhaust-nozzle having an unobstructed open upper end or outlet, of a flat plate B, having an unobstructed opening of the same size as the nozzle-outlet and pivotally connected with the nozzle to one side of its outlet to vibrate horizontally thereacross, substantially as set forth.
- 20 2. The combination, with the double nozzle, of a vibrating plate B on top thereof and provided with two apertures the same in size as the outlets of said nozzle, a pivot connecting the said plate between its apertures with the 25 nozzle between its outlets, and a cross-bar under which the center of said plate works, substantially as set forth.

3. In an exhaust-nozzle for locomotives, the combination, with a bar secured to the sides of the exhaust-pipe and a pin projecting from the said bar, of a plate pivoted loosely on the said pin and provided with apertures adapted to register with the openings in the exhaust-pipe, and projections formed on the top of the said plate to engage the under side of the said bar, substantially as shown and described.

4. In an exhaust-nozzle for locomotives, the combination, with a bar secured to the sides of the exhaust-pipe and a pin projecting from the said bar, of a plate pivoted loosely on the said pin and provided with apertures adapted to register with the openings in the exhaust-pipe, projections formed on the top of the said plate to engage the under side of the said bar, an arm projecting from the said plate, a lever pivotedly connected with the said arm, and a second lever under the control of the engineer in the cab of the locomotive and pivotally connected with said first-named lever, substantially as shown and described.

JOHN J. DE LANCEY.
